UNITED STATES PATENT OFFICE.

GEORGE TURNER AND WILLIAM H. SHOFTER, OF BARBERTON, OHIO, ASSIGNEES TO THE DIAMOND MATCH COMPANY, OF CHICAGO, ILLINOIS, A CORPORATION OF ILLINOIS.

MACHINE FOR MAKING MATCH BOOKS.

Application filed March 6, 1923. Serial No. 623,116.

To all whom it may concern:

Be it known that we, GEORGE TURNER and WILLIAM H. SHOFTER, both citizens of the United States, and residents of Barberton, in the county of Summit and State of Ohio, have invented certain new and useful Improvements in Machines for Making Match Books, of which the following is a specification.

10 This invention relates to machines for making match books, having reference more especially to the machine described in Letters Patent of the United States No. 1,042,472 dated October 29, 1912, wherein an endless carrier comprising links having holders for the associated covers and cards of match books, is employed, together with a mechanism operative to apply frictional ignition substance to the end folds of the 20 covers during their travel.

The object of our invention is to provide simple and efficient means whereby the uniform disposition of the succeeding books in respect to the "friction" applying mechanism, is ensured; and to that end we mount laterally of the carrier a rotary book-positioning element which co-operates with the adjacent end of each succeeding holder in such a manner as to shift the opposing book 30 to a definite position transversely of the carrier as the book approaches the friction applying mechanism.

The invention also comprises features of construction and combinations of parts which 35 will be hereinafter described and claimed.

In the drawings—

Figure 1 is a plan of a portion of a match-book machine equipped with book-positioning mechanism embodying our invention, a 40 succession of match covers being shown in the carrier of the machine.

Fig. 2 is a sectional elevation, as on the line 2—2 of Fig. 1.

Fig. 3 is a transverse vertical section, enlarged, through the carrier and associated parts, as on the line 3—3 of Fig. 2.

Fig. 4 is a perspective view of a portion of the carrier and the book-positioning mechanism, showing the rotary element of the latter as acting upon an opposing book during the movement of the carrier; the extended cover flaps of two of the match-books being removed for clearness.

Fig. 5 is a similar view showing the said

element in another position during its rotation.

Referring to the drawings, 10 designates a portion of the upper run of a carrier comprising an endless chain of hingedly connected links, each having a body portion 11 overhanging end flanges 12, and an inclined spring member 13, the whole constituting a holder for the associated cover 14 and cards 15 of a match book. The underside of the body is provided with rack 16 teeth 17.

The carrier is supported and guided upon a track structure 18 in the region of the friction applying mechanism, which mechanism includes a composition containing vessel 19, and a wheel 20 rotatable therein in a manner to apply the composition in a thin layer to the underside of the end folds of the succeeding covers as they progress above the wheel. This wheel is mounted on a suitably-disposed shaft 21 having a spur wheel 22 in mesh with a pinion 22 on a continuously driven shaft 23. Thus the wheel 19 is rotated.

In mesh with the rack teeth of the carrier is a gear wheel 24 which is mounted on a suitably-disposed shaft 25 having a spur wheel 26 in mesh with the pinion 22, and hence continuous motion is transmitted to the carrier in its travel in the region of the friction applying mechanism.

A freely rotatable pressure wheel 27 is mounted directly above the wheel 19 so as to bear upon the folded ends of the progressing book covers and ensure their efficient contact with the latter wheel.

28 designates a book-positioning wheel having a vertical axis (29) of rotation adjacent the outer side of the carrier and in proximity to the composition devices. This wheel is formed with a series of equally-spaced arms 30 which are so disposed that their outer ends are successively engaged by the book holders of the traveling carrier, such arms thus partially entering, advancing with and receding from the holders. The wheel rotates in a horizontal plane directly beneath that of the match-book covers, and hence as each arm enters or meshes with a holder the end of the arm bears against the opposing heads of the matches of the book contained in the holder and bodily pushes the book transversely of

the carrier and against a suitably-disposed stop 31 which insures the accurate alignment of the folded ends of the covers with each other and with the composition-applying wheel. This stop preferably comprises a metal plate secured to an arm or bracket 32 on the track structure 17.

In the present instance the axial stud 29 of wheel 28 is mounted on an arm 33 that is pivoted, as at 34, on a bracket 35 secured to the track structure, said arm 33 having an outward extension 36 which is resiliently connected to the bracket 35 by means of a spring 37 that tends normally to pull the arm 33 and therewith the wheel 28 toward the carrier. Extending through the arm is a set-screw 38 which bears against the side of the track structure and thus affords an adjustable stop by means of which the operative position of the wheel in respect to the carrier can be nicely determined. The spring ensures the yielding contact of the arms 30 of the wheel with the match books in the carrier, and thus prevents undue pressure of the arms on the match heads in the event of variations in the size of the match heads or in the attachment of the cards to the covers.

It is to be understood that we do not limit our invention to the particular construction herein disclosed, as the same may be modified within the principle of our invention and the scope of the appended claims.

We claim—

1. The combination with a carrier having a succession of holders for match-books, of a rotary book-positioning element mounted laterally of the carrier and operative to enter the adjacent end of each succeeding holder and shift the contained book therein transversely of the carrier.

2. The combination with a carrier having a succession of holders for match-books, of a rotary book-positioning element mounted laterally of the carrier and operative to enter the adjacent end of each succeeding holder and shift the contained book therein transversely of the carrier, and means for adjusting said element toward and from the carrier.

3. The combination with a carrier having a succession of holders for match-books,

of a freely rotatable wheel having its axis laterally of and at right angles to the path of travel of the carrier, and also having a series of spaced radial arms operative to enter the adjacent end of each succeeding holder and be advanced thereby in a manner to shift the opposing book transversely of the carrier.

4. The combination with a carrier having a succession of holders for match-books, of a freely rotatable wheel having its axis laterally of and at right angles to the path of travel of the carrier, and also having a series of spaced radial arms operative to enter the adjacent end of each succeeding holder and be advanced thereby in a manner to shift the opposing book transversely of the carrier, and means for adjusting said wheel toward and from the carrier.

5. The combination with a carrier having a succession of holders for match-books, of a freely rotatable wheel having its axis laterally of and at right angles to the path of travel of the carrier, and also having a series of spaced radial arms operative to enter the adjacent end of each succeeding holder and be advanced thereby in a manner to shift the opposing book transversely of the carrier, a pivoted arm on which the wheel is supported, a spring tending to move said arm inwardly toward the carrier, and a set-screw for determining the inward position of the arm.

6. The combination with a carrier having a succession of holders for match-books, means adjacent one side of the carrier for applying friction material to the succeeding books during their travel, and a stop for the ends of said books as they approach and pass the friction applying means, of a rotary book-positioning element mounted adjacent the opposite side of the carrier and operative to enter the adjacent end of each succeeding holder and shift the opposing book transversely of the carrier and against the end stop.

Signed at Barberton, in the county of Summit and State of Ohio, this 2d day of March, A. D. 1923.

GEORGE TURNER.
WILLIAM H. SHOFTER.
